UNITED STATES PATENT OFFICE.

STEPHEN JABLONOVSKY, OF BRIDGEPORT, CONNECTICUT.

ADJUSTABLE WINDOW-GRADE.

942,502.

Specification of Letters Patent. Patented Dec. 7, 1909.

Application filed June 25, 1909. Serial No. 504,218.

To all whom it may concern:

Be it known that I, STEPHEN JABLONOVSKY, citizen of the United States, and resident of Bridgeport, in the county of 5 Fairfield and State of Connecticut, have invented certain new and useful Improvements in Adjustable Window-Grates, of which the following is a specification.

My invention relates to new and useful 10 improvements in portable window grates and especially to the adjustable kind, adapted to be placed in or removed from a window opening.

It is the object of my invention to form 15 a window grating of the above class in sections, adapted to be assembled and adjusted with respect to each other so as to readily engage and cover a window opening, as beneath a sash; to form the grating of metal, 20 either cast or wrought, and to produce each section as of a series of bars suitably spaced apart in a way to prevent a person from passing in or out the window while the grating is in place, thus serving not only as 25 a protection against children falling out, but against intruders from entering through the window.

Upon the accompanying two sheets of 30 drawings forming a part of this specification similar characters of reference denote like or corresponding parts throughout the several figures and of which,

Figure 1, shows a front elevation of my 35 improved adjustable grating complete, and ready to be placed in a window opening. Fig. 2, is a similar front elevation of the several parts of my grating, in an expanded position, as for instance that occupied when arranged within a window opening, not 40 shown. Fig. 3, is a disconnected side elevation of the two upper sections of the grating shown in the preceding figures. Fig. 4, shows a similar detached side elevation of the two lower sections of the grating shown in 45 Figs. 1 and 2. Fig. 5, shows a disconnected top edge view of the parts shown in Fig. 4, and as seen from line 5 of Fig. 4, and Fig. 6, shows a sectional plan view taken on line 6—6 of Fig. 4.

Referring in detail to the characters of 50 reference marked upon the drawings, A and B represent the two upper sections of the grating while C and D represent the two lower sections. As shown each of these sections represents a united series of vertical 55 and cross bars formed integral as by means

of casting or welding. These sections are further provided with projections, guide holes, etc. to insure their adjustable connection one with the other to engage a window casing, not shown. Each of the sections referred to is provided with one or more extended yokes 7. Those of the lower sections being for the purpose of engaging the sides of the casing while those upon the 60 top sections are for the engagement of the lower part of the sash, thereby preventing the grating from falling out, or being removed, while the parts are in their extended 65 positions.

The sections A and B are each provided 70 with depending tongues 8—8 one upon the underside of each end to engage correspondingly vertically disposed sockets 9 in the top portion of the lower sections which serve as 75 an adjustable connection of the upper to the lower grate sections. A pawl 10 is pivotally connected to each of the lower sections C and D and is adapted to be thrown in under the end of the outer tongues 8 of each of the 80 corresponding top sections to hold the same in their raised position, as shown in Fig. 2. The section D is also provided with a central socket 11 at each of its upper and lower 85 inner corners to receive the reduced portion 12 of the adjoining lower section C whereby the two said members are horizontally adjustably connected one with the other. The same is true of the two upper sections in 90 which case the upper and lower inner corners of the section B are recessed as at 13 to receive the reduced corner portions 14 of the section A. The inner vertical part 15 of the section C is provided with a pair of notches 16 to engage the lugs 17 fixed to the 95 corresponding inner part 18 of the section C. In practice these lugs engage the notches and serve as a guide and lock for the same to prevent the said sections from being 100 slipped together when the locking bar 19 is arranged in front of it as shown in Fig. 2. The locking bar is hinged to the top section B as at 20 and is arranged vertically as shown in Fig. 2 behind the projections 21 of the section C and is further cut away as 105 at 22 to accommodate the lugs 17, and its lower end is deflected in and provided with a slot 23 to engage a staple 25 secured to the face or apron of a window frame. A lock 24 may be thus applied through the staple 110 as shown in Fig. 2, in a manner to prevent the lower sections from being slid toward

each other and the central portion of the top section from being lowered thus retaining the several parts in their extended positions to be firmly secured in the window opening 5 as described.

Having thus described my invention what I claim and desire to secure by Letters Patent is:—

1. A window grating comprising a pair of 10 grate sections adjustably connected one to the other, a second pair of grate sections also slidably connected one with the other and arranged above the first said sections and adjustably connected therewith, and 15 means for securing the said sections in their extended positions within a window frame.
2. A window grating comprising a pair of

grate sections adjustably connected one to the other, a second pair of grate sections also slidably connected one with the other 20 and arranged above the first said sections and adjustably connected therewith, a locking bar pivotally connected to one of the upper sections to hold the same in an extended position and adapted to be fastened to a 25 window frame to hold the sections within the same.

Signed at Bridgeport, in the county of Fairfield, and State of Connecticut, this 17th day of June, A. D., 1909.

STEPHEN JABLONOVSKY.
